UNITED STATES PATENT OFFICE.

FRANK FIELD GARRARD, OF DALLAS, TEXAS.

DESIGN FOR A BOTTLE.

SPECIFICATION forming part of Design No. 35,443, dated December 17, 1901.

Application filed October 19, 1901. Serial No. 79,311. Term of patent 3½ years.

To all whom it may concern:

Be it known that I, FRANK FIELD GARRARD, a citizen of the United States, residing at Dallas, in the county of Dallas and State of Texas, 5 have invented and produced a new and useful Design for a Bottle, of which the following is a specification.

The essential feature of the design resides in the peculiar shape of the bottle herein described, and shown in the drawings forming a part of this specification.

Figure 1 is a perspective view of a bottle constructed in accordance with my design, and Fig. 2 is a cross-sectional view taken 5 through the body of the bottle.

Referring to the drawings, A indicates the body of the bottle, and B the neck of the said bottle. The body of the bottle is essentially triangular in cross-section, the sides or faces of the bottle being flat and the vertical edges A' being rounded or curved. The neck B is

of substantially the same length as the body of the bottle and tapers gradually toward the mouth. At the juncture of the neck and body, at each side of the body, is the curved shoulder C, and between the said shoulder C and the tapering portion of the neck is the inwardly-curved portion D. The bead B' is produced upon the exterior of the neck adjacent to the mouth. The series of parallel marks 30 E are produced upon one of the curved edges of the bottle.

The bottom of the bottle is flat.

Having thus fully described my invention, what I claim as new, and desire to secure by 35 Letters Patent, is—

The design for a bottle, substantially as herein shown and described.

FRANK FIELD GARRARD.
